[57] CLAIM

The ornamental design for an adjustable stroller, as shown and described.

DESCRIPTION

FIG. 1 is a front perspective view of an adjustable stroller showing my new design;

FIG. 2 is a rear perspective view thereof;

FIG. 3 is a top perspective view thereof;

FIG. 4 is a side perspective view thereof, the opposite side being a mirror image of that shown;

FIG. 5 is a front perspective view thereof;

FIG. 6 is a rear perspective view thereof;

FIG. 7 is a perspective view thereof in an alternate position;

FIG. 8 is a side perspective view of FIG. 7;

FIG. 9 is a perspective view thereof in a second alternate position;

FIG. 10 is a side perspective view of FIG. 9;

FIG. 11 is a front perspective view of FIG. 9; and

FIG. 12 is a rear perspective view of FIG. 9.

FIG.1.

FIG.2.

FIG.3.

FIG.4.

FIG.5.

FIG.6.

FIG. 7.

FIG. 8.

FIG. 9.

FIG. 10.

FIG II.

FIG.12.
